UNITED STATES PATENT OFFICE.

SAMUEL B. ZIMMER, OF LOS ANGELES, CALIFORNIA, ASSIGNOR, BY DIRECT AND MESNE ASSIGNMENTS, OF TEN PER CENT TO EDWARD C. EDDIE, OF SOUTH PASADENA, CALIFORNIA, AND NINETY PER CENT TO PAUL B. TICKENOR, OF SALT LAKE CITY, UTAH.

ADJUSTABLE STAFF MOLD FOR WINDOWS.

Application filed January 5, 1926. Serial No. 79,462.

This invention relates to improvements in staff molds and jambs for windows and similar closures for wall openings.

An object of this invention is to provide a window jamb with an adjustable staff mold which permits the construction of variously sized windows, and which will permit the mounting of these windows in a wall opening which may not have the exact size corresponding to the window dimensions. In other words, in constructing a building an opening may be left in the wall which is of a size somewhat larger than the window which is to be used. A window is selected which will be receivable within the opening, and by means of the improved jamb and adjustable staff mold the window can be caused to fit the opening. The improved construction is quite important in that in constructing brick walls with wall openings it is unnecessary to cut any brick. The brick may be laid in any bond and any desired joint, and when the wall has been completed, by ascertaining the dimensions of the wall opening the window of the nearest size which will fit within the wall opening is selected and the adjustable jamb and staff mold will cause it to fit, although the width of the wall opening may vary.

With the foregoing and other objects in view which will be made manifest in the following detailed description and specifically pointed out in the appended claims, reference is had to the accompanying drawings for an illustrative embodiment of the invention, wherein:

Figure 1 is a side elevation of a portion of a brick wall having a wall opening therein, in which the improved jamb and adjustable staff mold have been mounted,

Fig. 2 may be considered as a horizontal section taken upon the line 2—2 of Fig. 1,

Fig. 3 is a perspective view of a portion of the improved staff mold,

Fig. 4 is a perspective view of a portion of the jamb used in connection with the staff mold, and

Fig. 5 is a horizontal section similar to Fig. 2, illustrating a slightly modified form of construction.

Referring to the accompanying drawings

wherein similar reference characters designate similar parts throughout, the wall is generally designated at 10 having an opening 11 provided in it. The invention consists of a jamb, generally designated at 12, which has a front wall 13 and side walls 14 and 15. The adjustable staff mold associated with the jamb consists of a securing part 16 adapted to be secured against the side 55 of the wall opening 11. This securing part has a plurality of apertures 17 for the reception of brick screws or similar fastening elements 18 in securing the staff mold to the side of the wall opening. The staff mold has a portion 19 bent at right angles to the securing part 16 and to the side of the wall opening. It is also provided with a portion 20 arranged parallel to but spaced from the securing part 16 and with a portion 21 60 which extends towards the side of the wall opening. The particular form or arrangement of the two portions 20 and 21 is immaterial, and, if desired, this may be changed to present an ornamental appearance. The essential characteristics of these two portions is that they combine to form a part extending from the forward edge of the portion 19 rearwardly and outwardly toward the side of the wall opening 11. The 65 edge of the portion 21 is preferably reversibly bent upon itself, as indicated at 22, for purposes of stiffening.

An angular member has a portion 23 positioned against the securing part 16. This 70 portion is rigidly secured to the securing part as by spot welding, riveting, or the equivalent. The angular member also has a portion 24 which is arranged at right angles to the portion 23 and adjacent the portion 19 of the staff mold. The forward edge of the portion 24 is preferably reversibly bent upon itself, as indicated at 25, for purposes of stiffening. The side 15 of the jamb is disposed between the portions 19 and 24 75 and is frictionally held between these portions.

In mounting the jamb and staff mold upon the wall, the staff mold together with the angular member can be secured in place by 80 means of the brick screws or fastening elements 18. After it has been so mounted and

the jamb applied, the side wall 15 is caused to slide between the portions 19 and 24, thus permitting the adjustment of the jamb relatively to the staff mold or vice versa.

5 In this form of construction, which is shown in Fig. 2, the jamb and staff mold have been primarily designed for use upon brick and concrete walls. In mounting the staff mold upon such walls, it may sometimes be found desirable to take a brick saw or equivalent instrument and cut a groove in the side of the wall opening 11 for the reception of the reversely bent portion 22 of the portion 21 of the staff mold, thus presenting a neat and finished appearance. This construction, however, is optional.

The advantages and utility of the improved construction are as follows: In constructing the wall 10 the wall opening 11 is formed therein. In forming this wall opening, the bricklayer or mason does not cut any brick, but merely lays out the brick in any desired bond and any desired joint so that the width and height of the opening are the next oversize as permitted by the brick over the desired window dimensions. The windows are constructed of various widths which vary at about half brick lengths. Their heights can be varied by thicknesses of bricks. After determining the dimensions of the wall opening 11, which has been left by the mason or bricklayer, that window is selected which is the next size smaller than the dimensions of the wall opening 11. The staff molds are secured in place and the jambs 12 are applied. These jambs are then adjusted so that they will fit the window selected. After the jamb has been adjusted, the inside finish plaster P can be applied, and that portion of the plaster which extends upon the side of the wall opening 11 is caused to join the edge of the side wall 14 of the jamb 12, thus holding the jamb in its adjusted position. After the jambs have been set, the window guides of any desired construction can be secured to the front wall 13, and any cross braces which may be used in a plural sash window can also be applied. At the same time, the head and sill can be positioned over the top of the staff mold and jamb and beneath the staff mold and jamb respectively.

Because of the fact that the improved jamb and adjustable staff mold provide an adjustment, it will be readily appreciated that it is only necessary to construct and keep in stock a set of windows varying in width by half brick lengths and in height by brick thicknesses, and that these windows can be used regardless of the particular sizes of wall openings formed by the various masons. The adjustment between the staff mold and the jamb is preferably not less than one-fourth of a brick length,

so that when two jambs with their adjustable staff molds are used, the dimension between the front walls 13 of the two jambs can be varied at least one-half of a brick length and thus accommodate any window. 70

The above mentioned construction is primarily designed to be used upon brick and concrete walls.

In the modification shown in Fig. 5, the jamb and adjustable staff mold have been primarily designed to be used upon stucco or plaster walls. These walls consist of studs S, against the inner side of which there is adapted to be positioned plaster P, and against the outer sides of which there may be applied stucco or plaster O. In this modification, the jamb has a front wall 13 and the side walls 14 and 15, and the staff mold has the securing part 16 and the portions 19, 20 and 21. The edge of the portion 21, however, instead of being reversely bent upon itself, is provided with a hooked flange 26, constituting a ground or guide for the outside plaster O, and behind which the plaster may be positioned to lock the edge of the staff mold in place. The adjustment of the jamb 12 between the portions 19 and 24 is the same as in the modification shown in Fig. 2. This jamb and adjustable staff mold are used in the same manner as before, it being merely necessary to select the window which is the next size smaller than the window opening, position the staff molds and jambs in place and thus cause the window to fit the opening. In this modification, however, the side wall 14 is preferably caused to assume a position flush with the surface of the plaster P, as determined by the plaster ground 27. As the thickness of the outside plaster O may vary in some instances, it may be necessary to especially construct the staff mold so that the distance between the flange 26 and the side wall 14 will be equal to the thickness of the wall. 95

From the above described construction it will be readily appreciated that the improved jamb and adjustable staff mold will eliminate the cutting of brick in forming brick wall openings. Furthermore, it will permit various windows to be kept in stock and the windows selected which will fit the various openings. As the staff mold and jamb are formed of metal, they form a fire-proof window casing, and also a casing which is very rigidly held in place, and which will be strong and durable. 110

It will be understood that various changes in the detail of construction may be made without departing from the spirit or scope of the invention as defined by the appended claims. 115

I claim:

1. A device of the class described comprising a staff mold having a securing part adapted to be secured to the side of a wall 120

- opening, a portion at right angles thereto and a portion extending toward the side of the wall opening from the last mentioned portion, an angular member having a portion fastened to the securing part and another portion disposed adjacent the portion of the staff mold at right angles to the side of the wall opening, and a jamb having a front wall and two side walls, one of the side walls being receivable between the portions of the angular member and staff mold arranged at right angles to the sides of the wall opening.
2. A device of the class described comprising a jamb having a front wall, two side walls, and a staff mold having two parallel portions between which is frictionally and adjustably held one of the side walls only of the jamb.
3. A device of the class described comprising a staff mold adapted to be secured in the side of a wall opening, a jamb, said jamb being adjustable relatively to the staff mold so as to be adjustable toward and away from the side of the wall opening, said jamb and staff mold being secured together solely by frictional engagement with each other.
4. A device of the class described comprising a jamb presenting a side which is adapt-
ed to be arranged so as to extend towards the sides of a wall opening, and a staff mold adapted to be attached to the side of the wall opening, said staff mold being connected to the jamb by parts which embrace the inside and outside surfaces of the said side, permitting of the adjusting of the jamb relatively to the staff mold but holding it frictionally in adjusted position.
5. A device of the class described comprising a jamb channel shaped in cross section and a staff mold, the staff mold consisting of two sheet metal parts one having a securing portion adapted to be fastened to the side of the wall opening and another portion extending outwardly therefrom, the other part having a portion secured to the securing portion and another portion arranged adjacent the outwardly extending portion on the first part, one side of the jamb being disposed between the outwardly extending portions on said parts and being frictionally held thereby, thus providing for adjustment of the jamb relatively to the staff mold but frictionally holding the jamb in any adjusted position.

In testimony whereof I have signed my name to this specification.

SAMUEL B. ZIMMER.
